UNITED STATES PATENT OFFICE.

WILLIAM J. DAVIDSON, OF BIG SPRING, VIRGINIA.

PLOW.

SPECIFICATION forming part of Letters Patent No. 307,919, dated November 11, 1884.

Application filed February 20, 1884. (No model.)

To all whom it may concern:

Be it known that I, WM. J. DAVIDSON, of Big Spring, in the county of Montgomery and State of Virginia, have invented certain new and useful Improvements in Plows, of which the following is a specification.

My invention is a plow having a beam in two parts connected, to secure a continuous rigid structure, with interposed elastic material confined under compression, so that the danger of breaking is lessened and the plow-blades or cultivator-teeth will be caused to adapt themselves to hard and soft land.

In the accompanying drawings, Figure 1 shows a plan view of a double plow with my invention attached thereto. Fig. 2 shows a similar view of my invention applied directly to the plow or cultivator beam. Fig. 3 is a sectional view. Fig. 4 is a perspective view 20 of the parts detached, and Fig. 5 is a side view of a modification.

Heretofore it has been common to make the teeth of drills and the like adjustable and yielding; but this involves a considerable expense, and the means of doing so are comparatively complicated and liable to get out of order, and the means adopted are not well adapted to plows and cultivators. I accomplish the result by a very simple arrangement that can 30 be easily adapted to plows and cultivators now in general use at very little expense, and when applied is not liable to get out of order.

Referring to Fig. 1, which shows one form of cultivator, the beam A is made with a curved neck, a, the handles B being pivoted at x to the beam and adjustably secured to the neck. On one or both sides of the beam A are secured brackets D D, of any desirable shape or form, and to the brackets are secured the standards 40 C C.

Between the beam A and the brackets D, I interpose a spring device, as blocks E, of some elastic or yielding material, preferably of rubber. In order to get the proper bearing upon the blocks, and to hold them in position, I provide clamps or plates F F, having at each end flanges f f, preferably bent in opposite directions, and through the centers of the clamps I provide elongated holes or slots s. Bolts G G 45 pass through the beam A, blocks E, clamps F, and through the brackets, and are secured outside thereof by nuts. From this construc-

tion it will be seen that the brackets are secured to the beam in a yielding manner, one of the flanges f of one of the plates or clamps F bearing upon one edge of the bracket, and the other flange bearing upon the elastic or yielding block, and one flange of the other clamp bearing upon one edge of the beam, and the other flange bearing upon the opposite side 60 of the yielding block, and when any pressure or strain is caused to bear upon the brackets the clamps will tend to compress the yielding blocks between their opposite flanges and allow a movement of the bracket more or less 65 depending upon the adjustment of the initial pressure upon the blocks caused by the screw-bolts. Not only will this arrangement allow of a movement in a vertical direction, but also in a horizontal direction, and both of these 70 movements may be adjusted or regulated by the initial pressure upon the yielding or elastic blocks caused by tightening or loosening the nuts upon the bolts.

In Fig. 2 I have shown a beam, A, made in 75 two parts, which are secured together by means of my improved arrangement, so that they may yield in the manner heretofore pointed out. In this arrangement the standards may be secured to the beam directly or by 80 brackets, as described in reference to Fig. 1. In a single plow I prefer to secure the beam adjustably; but in a double plow or cultivator I prefer to secure the brackets adjustably to the beam.

Instead of forming the clamps of separate pieces, the flanges may be cast upon or otherwise secured to the beam and brackets; and, instead of having two sets of clamps, one may be used, the flanges being turned in the proper directions to bear upon the beam and the yielding material; and, instead of two bolts passing through the blocks and clamps, a single bolt may be used to hold the bracket to the beam, passing through the bracket and beam between the blocks, or through a single block, as shown in dotted lines Fig. 2. In some cases where more movement is desired the holes either in the beam or bracket, or both, may be made oblong transversely thereto, as 95 indicated in dotted lines.

The standards may be attached directly to the clamps independent of the bracket.

Many modifications will suggest themselves

which may be made without departing from the spirit of my invention, which consists in attaching the parts of a plow or cultivator together by the means described, so as to form 5 a practically rigid structure, but one that will yield slightly to pressure, so as to prevent breaking of the parts by any sudden shock or jar, and so that the plow or cultivator will be adapted for all kinds of land, whether hard or 10 soft.

In some instances where the above-described arrangement does not give sufficient amount of yielding movement the standards may be attached to the bracket or to the beam, so as 15 to yield before they will break, and to accomplish this I provide a longitudinal slot, *m*, as shown in my Patent No. 254,932, in the beam or bracket, and an inclined notch, *n*, through which the bolts securing the standard are 20 passed. If the strain upon the parts is too severe, the pressure of the standard against the edge of the inclined slot will cause the bolt in the slot *m* to move forward slightly, when the bolt in notch *n* will slip out of place, allowing 25 the standard to give way under the strain without breaking.

I do not herein claim, broadly, the use of

springs or cushions to prevent the injurious effects of shocks or strains upon the plow or cultivator.

30

I claim—

1. A plow having a beam in two parts connected, to secure a continuous rigid structure, with interposed elastic material confined under compression, substantially as and for the purpose set forth. 35

2. The beam *A*, in combination with the bracket *D*, the yielding or elastic block *E*, the clamps *F* *F*, having flanges *ff*, and means for securing the same together, as set forth. 40

3. The combination, with the beam or bracket provided with the elongated slot *m* and inclined notch *n*, of the standard secured thereto by bolts, the arrangement being such that upon too great strain upon the standard the bolt will slip from the notch *n*, as set forth. 45

In testimony whereof I have signed my name to this specification in the presence of two subscribing witnesses.

WM. J. DAVIDSON.
